UNITED STATES PATENT OFFICE.

CHARLES D. LANNING, OF BOSTON, MASSACHUSETTS, ASSIGNOR TO AMERICAN WARP DRAWING MACHINE COMPANY, A CORPORATION OF MAINE.

WARP-THREAD-HOLDING DEVICE.

1,267,089.

Specification of Letters Patent. Patented May 21, 1918.

Application filed April 17, 1912. Serial No. 691,276.

To all whom it may concern:

Be it known that I, CHARLES D. LANNING, a citizen of the United States, and a resident of Boston, county of Suffolk, and State of Massachusetts, (whose post-office address is 95 Milk street, Boston, Mass.,) have invented an Improvement in Warp-Thread-Holding Devices, of which the following description, in connection with the accompanying 10 drawings, is a specification, like characters on the drawings representing like parts.

This invention relates to warp thread holding means and more particularly to means for holding the threads of a warp in 15 the relation in which they come from the slasher. The invention will be best understood by reference to the following description when taken in connection with the accompanying illustration of one specific embodiment thereof, while its scope will be 20 more particularly pointed out in the appended claims.

In the drawings:

Figure 1 is an elevation of a warp beam 25 to the warp in which there is applied one form of my invention;

Fig. 2 is an end elevation partly in section of the warp and warp beam shown in 30 Fig. 1;

Fig. 3 is a detail in front elevation of the warp holding device;

Fig. 4 is a sectional elevation taken on the line 4—4 in Fig. 3;

Fig. 5 is a front elevation of a modified 35 form; and

Fig. 6 is a section taken on the line 6—6 in Fig. 5.

In order to hold the ends of the warp threads in parallel arrangement and in the 40 relation in which the warp comes from the slasher it has heretofore been a frequent practice to apply to the threads of the warp a flexible holding member such as a strip of adhesive tape. This is usually done while 45 the warp is still in the slasher and before severance therefrom so that the threads being severed closely adjacent the tape are held in the same established relation which they occupied in the slasher. The beam can 50 then be transported from place to place or the end of the warp handled or moved about for installation in a warp drawing-in, warp-

tying machine or other machine with assurance that the established relation of its thread ends will be maintained.

55

A flexible tape, however, while cheap, simple, economical and occupying a very small space has the disadvantage that it is not easy to grasp in the hands or is apt to tear if grasped in one or two places for the purpose 60 of lifting or pulling the end of the warp. Furthermore, being flexible, it does not maintain the threads stretched but is apt to bend, flex, buckle or double over so that the threads, while held on the tape itself in a 65 parallel sheet, are not necessarily so held on either side of the tape where they may be crossed, due to the flexing of the tape. This renders uncertain any subsequent operation 70 which depends upon the parallel relation of the threads, as for example, the application thereto of a clamp in a warp drawing machine.

My invention contemplates the employment of thread holding means which is 75 adapted to hold the threads in the form of a flat sheet and which is also capable of being easily grasped, whereby the end of the warp may be pulled about as when fastened by a clamp.

80 Preferably, though not necessarily, I employ a flexible holding member such as a strip of adhesive tape with provision, however, for applying thereto relatively rigid stiffening means. In the form shown in 85 Figs. 3 and 4, the holding member comprises a flexible member 1 which may be of paper or other suitable material fastened transversely across the warp threads 2, the latter being represented in Fig. 1 as wound upon 90 the warp beam 3. The flexible holding member 1, which may be prepared with one side gummed, is made in the form of a flattened tube, the gummed side being adhesively applied to the warp. When thus applied, as 95 shown in Fig. 1, it lies flat across the threads and resembles the holding tape of the prior art. To stiffen the tape, however, there may be inserted in the tube at any time the longitudinal stiffening member 4 which herein is 100 shown in the form of a rod having a pointed end 5 to facilitate its ready insertion in the tube, such rod extending preferably for substantially the entire length of the holding

member. The rod may be of metal or wood, and may be of any desired cross sectional shape, but preferably it is more or less flattened so as to avoid undue thickness. When 5 the rod is inserted the threads are held in a flat stretched sheet and may be pulled or drawn taut as in the case of a clamp, by seizing the holder at one or more points, the holder being readily grasped by the hands 10 of the operator. This greatly facilitates the handling of the warp and renders more certain the parallel relation of the threads.

The stiffening member may be shorter than, or coextensive in length with, the flexible strip, but herein I have shown it as projecting beyond the ends of the latter, this making it possible to support the end of the warp in a rack or the like for purposes of examining, manipulating or operating on 20 the threads while thus held.

In Figs. 5 and 6, I have shown a modified form of the invention wherein a flat strip of ordinary adhesive tape 6 is employed, this being stuck transversely across the warp 25 threads as usual. Depending from this tape, however, at suitable intervals, there are provided looped tabs 7 through the loops of which the stiffening member 8 is inserted, performing substantially the same function 30 as the stiffening member 4 in Figs. 3 and 4.

Other means may be employed for carrying out some or all the purposes of this invention, but the foregoing embodiments will suffice to illustrate the principles thereof.

Copies of this patent may be obtained for five cents each, by addressing the "Commissioner of Patents, Washington, D. C."

Claims:

1. The combination with a warp of a stiffened holder adhesively secured transversely the threads of the warp. 35
2. The combination with a warp of a holder adhesively secured transversely the threads to maintain them in parallel relation, and means for stiffening said holder. 40
3. The combination with a warp of a thread holder, adhesively applied transversely the warp threads, and means thereon 45 for receiving a rigid member.
4. The combination with a warp of a tubular thread holder adhesively applied transversely the threads, the tubular member being adapted to receive a rigid stiffening rod. 50
5. The combination with a warp of a thread holder applied thereto consisting of a gummed tubular paper strip. 55
6. The combination with a warp of a rigid member and means for adhesively securing the same transversely the warp threads.
7. A warp having a flexible holder adhesively attached transversely thereto, and means for receiving a stiffening member applied thereto. 60

In testimony whereof, I have signed my name to this specification in the presence of two subscribing witnesses.

CHARLES D. LANNING.
